[57] ABSTRACT

This invention consists of a recreational and exercising device which is suspended by its center from a ceiling or an upper structural part. The device has, extending downwardly from its center and on each side thereof, a plurality of diverging arms which support a hand gripping bar. This hand gripping bar is free to rotate within the diverging arms. A person or persons using the device, grip the bars, one in each hand, and are thereby suspended freely in the air, whereupon they can swing or perform various forms of gymnastics for pleasure or exercise.

FIG.1

FIG.2

FIG.3

**SUSPENDED RECREATIONAL DEVICE WITH
ROTATABLE ROD STRUCTURE**

This invention consists of a device by means of which a person or persons can suspend themselves in mid air for the purpose of swinging or performing various gymnastics.

At the present time various recreational units such as swings, slides, merry-go-rounds, etc., are provided in public parks, school gymnasiums, and private homes, for the entertainment of children. These are not always available because of the high cost of such equipment and the large areas required for their installation.

The object of this invention is to provide a recreational device which is simple in construction, relatively inexpensive, and which can be installed in the home, in comparatively small outdoor areas, or as an adjunct to existing recreational equipment.

In describing the invention reference will be made to the attached drawings in which,

FIG. 1 is a plan of the invention,

FIG. 2 is an elevation of the invention, and

FIG. 3 shows one means of suspending the invention.

In the drawings the device 1 is shown consisting of a central heavy section 2 which is provided with a central hole 3. Extending downwardly from the central section 2, and on each side thereof is a central arm 4, and on each side of each of said arms 4 is a diverging arm 5. The arms 5,5, are equally spaced from and in the same plane as the central arm 4.

The ends 6 of the arms 4 and the ends 7,7, of the arms 5,5, are in line with and parallel to each other, and are provided with a hole 8 in the central arm 4, and a hole 9 in each of the arms 5.

A bar 10 which may be solid or in the form of a metal pipe, passes through the holes 8 and 9 on each side of the device and is held within these holes by means of cotter pins 12,12, at each end thereof. Other standard means maybe used for preventing the bar from sliding out of the said holes.

The diameter of the bars 10,10, is such that said bars are freely rotatable within the holes 8 and 9.

A washer 11 is provided between the cotter pin 12 and the arm end 7.

The installation of the device consists of passing a rope or cable 13 through the hole 3 in the center sec- 45

tion 2. After the rope is passed through the said hole, a knot 14 is tied in the end of the rope to keep the rope attached to the device. The other end of the rope is tied to a hook or to some structural part in the ceiling indoors, or to a tree branch outdoors.

After the device has been properly and safely suspended, a person grips each bar 10 with one hand and proceeds to swing from it in a to and fro or rotating motion, and at the same time performing various forms of 10 gymnastics. The spread between each pair of diverging arms 5,5, can be made large enough to accommodate one or several persons at the same time.

To start with, the device is suspended to within reach of the average individual who will be using it. To shorten the length of the rope 13, it is not necessary to 15 retie the knot 14, but merely to wind the said rope once or several times around the central section 2.

The device can be made of various materials which are strong enough to support one or more paersons. A 20 preferred method of manufacturing the device is to cast it in steel and cover the entire unit with a plastic coating.

Having described the invention, what I claim is:

1. A rope or cable suspended recreational and exercising device for hand gripping and swinging therefrom comprising a central heavy section with a vertical central hole therethrough; a central arm extending from each side of said central section at a downward angle; two diverging arms extending from each side of said central section, at a downward angle one on each side of said central arm and equally spaced from it, the ends of said central and diverging arms being lined up with and parallel to each other; holes in the ends of said arms; a rod passing through and rotating freely in the holes in the ends of said arms on each side of said central section; a cotter pin at each end of said rods for retaining the rod within said holes; and a washer between each of said cotter pins and adjoining arms.

2. A device such as described in claim 1, in combination with a rope or cable, which passes through the vertical hole in said central section, by means of which said device is suspended, and a knot tied in the end of said rope after passing through said hole by means of which said rope is attached to the device.
